RETORET CLEAN-OUT MACHINE

Hugh R. MacMichael, El Paso, Tex., assignor to
 American Smelting & Refining Company, New
 York, N. Y., a corporation of New Jersey

Application July 29, 1932, Serial No. 625,736

7 Claims. (Cl. 214—24)

The invention relates to apparatus for operating upon furnaces and the like, and more particularly to apparatus for cleaning zinc furnaces.

5 According to one form which the invention may assume, the apparatus may comprise a carriage adapted to move along the front of a zinc furnace and carrying tools for operating upon the several retorts of the furnace. The carriage 10 may support an elevator device, which in turn may support a carrier which carries the several tools.

Suitable means may be provided for driving 15 the carriage back and forth along the front of the furnace. Additional apparatus may be provided for raising the elevator device up and down and further apparatus may be provided for driving the carrier toward and away from the furnace so that the several tools may enter 20 the various retorts for operating thereupon. All of these driving apparatus may be under the control of a single operator, if desired.

Although different tools may be used, for purposes of illustration, a drag tool is taken having 25 a substantially vertical blade with a curved lower edge and mounted upon the end of a long shaft, the other end of which is mounted on the carrier by suitable spring devices. If desired, suitable cooling means may be provided for cooling the 30 tools and shafts. If desired, the mechanism for raising and lowering the elevator device and for moving the carrier toward and away from the furnace may be hydraulically operated. Water pressure may be supplied by a suitable centrifugal 35 pump operated by a motor on the machine.

The invention also consists in certain new and original features of construction and combinations of parts hereinafter set forth and claimed.

Although the novel features which are believed 40 to be characteristic of this invention will be particularly pointed out in the claims appended hereto, the invention itself, as to its objects and advantages, and the manner in which it may be carried out, may be better understood by referring 45 to the following description taken in connection with the accompanying drawings forming a part thereof, in which

Fig. 1 is a vertical elevation illustrating the 50 relation of the clean-out machine and the zinc retort furnace;

Fig. 2 represents an end elevation taken on section 3—3 of Fig. 2 of the machine;

Fig. 3 is an enlarged side elevation;

Fig. 4 represents a section on the line 4—4 of 55 Fig. 3;

Fig. 5 is a top plan view of the machine; Fig. 6 is a section on the line 6—6 of Fig. 3; Fig. 7 is a diagrammatic perspective illustrating the hydraulic rope operating mechanism; Fig. 8 is a detail with parts broken away showing the mounting of the tools on the carrier; Fig. 9 is a top plan view of the carrier; Fig. 10 is a section on the line 10—10 of Fig. 8; Fig. 11 is a perspective illustrating the construction of the elevator device; and

10 Figs. 12 and 13 illustrate two of the valves employed for controlling the operation of the machine.

In the following description and in the claims, various details will be identified by specific names 15 for convenience, but they are intended to be as generic in their application as the art will permit.

Like reference characters denote like parts in the several figures of the drawings.

In the drawings accompanying and forming 20 part of this specification, certain specific disclosure of the invention is made for purposes of explanation, but it will be understood that the details may be modified in various respects without departure from the broad aspect of the invention. 25

Referring now to the drawings, and more particularly to Fig. 1, the zinc retort furnace used for purpose of illustration is indicated by 10 and contains a plurality of vertical rows or tiers of retorts indicated by 11. It will be noted that 30 the retorts 11 are slightly inclined, as will be understood by those skilled in the art. This furnace may be of any desired construction.

Referring now to Figs. 2 and 3, a pair of track rails 23 may be disposed along the front of the 35 furnace 10 to support a carriage 20 resting upon a pair of I-beams 21 which are supported by four wheels 22 riding on the rails 23.

The carriage 20 is made up of suitable structural members, the lower frame members being 40 indicated by 30, these members supporting opposite inclined frame members, indicated by 31, which in turn support upper frame members, indicated by 32. The inclined members 31 support an intermediate platform, indicated by 132, 45 which supports the hydraulic and rope mechanisms for operating the carrier 25. The carriage frame 20 also supports a tall vertical tank 33 for holding the water for cooling the tools and for operating the hydraulic mechanism.

Vertically mounted on the frame 20 is an elevator device 24 (Fig. 11) having vertical guide columns 34 and horizontal frame members 35 connecting the vertical columns 34. The inclined track member 36 on which the carrier 25 55

rides also connects the vertical columns 34. The vertical guides 34 slidably fit guides 134 on the carriage frame 20, as illustrated best in Fig. 6.

Mounted on the inclined track 36 is a carrier 25 which supports the cleaning tools 26. As shown best in Figs. 1, 3, 8, 9 and 10, carrier 25 is made up of suitable structural members, at the upper ends of which are disposed two side plates 40 connected by connecting members 41 (Figs. 8, 9 and 10). In these side plates 40 are journaled four ordinary flanged wheels riding on the lower flanges of the inclined I-beam track member 36. The wheels 37 also engage rails 38 at the upper sides thereof, these rails being connected to the I-beam 36 by member 39. This construction gives stability to the carrier and prevents undue swaying thereof.

The carrier 25 has mounted thereon enough tools for operating upon a single vertical tier of retorts 11, four being shown for purposes of illustration. As shown best in Figs. 4 and 8, the tools 26, which are similar to drag tools, comprise substantially vertical flanges 42 having curved lower edges. These flanges are suitably welded or otherwise secured to outer tubular shafts 43 slidably mounted in fixed holders 44 and in spring holders 45. Springs 46 are provided for taking up bumps lengthwise of the tool in case the tool accidentally engages the end of a retort. The springs of holders 45 take up the up and down bumps and resiliently support the tools so that the weight of the tools firmly hold the flanges 42 thereof against the bottoms of the retorts for efficient cleaning and scraping.

For cooling the tools, inner pipes 49 are provided, spaced from the hollow shafts 43 and extending substantially the entire length thereof, these pipes being connected to feed branch pipes 50, passing through fittings 47 connected in the length of shaft 43. Branch outlet pipes 48 are connected to the fittings 47 for leading away the heated cooling water. It will be understood that the branch supply pipes 50 are fed from the discharge of the pump and the branch outlet pipes 48 lead to the cooling tank 33, as will be explained hereinafter more in detail.

For driving the carrier 25 back and forth along the track 36 to cause the tools to enter into and pass out of the retorts, suitable hydraulic and rope mechanisms, shown best in Figs. 3 and 7, are provided.

Mounted upon the platform 132 is a hydraulic cylinder 55 containing a piston 56 connected to a piston rod 57 which in turn is connected to cross head 58. Cross head 58 is suitably guided on the platform 132 and rotatably supports sets of cross head sheaves 59 and 60. It will be noted that the carrier drive mechanism is not mounted upon the elevator 24, but is mounted directly on the frame 20 of the carriage. This is permissible since the movement of the elevator is quite small and it is desirable not to have to raise and lower this additional operating mechanism. If desired, this operating mechanism may, of course, be mounted directly on the elevator device 24.

For moving the carrier 25 toward the furnace, fixed sheaves 66, cooperating with the set of movable sheaves 60, are provided. The rope 67 passes around the sheaves 60 and 66 and is fixed at one end to the carrier 25 at 68, and at the other end to the frame at 69. In order to avoid too great a tension on the rope 67, the rope is passed over a safety pulley 71, and over a fixed pulley 70. Safety pulley 71 is mounted on a

cross head 72 which slides between ways 73. Tension is maintained in the rope 67 by a counterweight 76 connected to the cross head 72 by rope 89 and passing over fixed pulleys 75. A movable electric contact 77 is carried by cross head 72 adapted to contact with a fixed electrical contact 78 if excessive tension in rope 67 is obtained, the engagement of these contacts operating the circuit breaker of the motor which drives the centrifugal pump supplying the cylinder 55, as will be explained hereinafter more in detail.

For withdrawing the tools out of the furnace, a movable set of sheaves 69 and fixed sheaves 61 are provided, over which rope 62 passes, the ends of this rope being secured to carrier 25 at 64 and to the frame member 132 at 65.

It will be noted that sufficient plies of rope for both movements of the carrier are provided so that a small movement of piston 56 will cause an increased movement in the carrier 25. In the form shown six plies are used for each movement, resulting in six times as great a movement for the carrier 25 as for the piston 56.

For driving the elevator device 24, water cylinder 80 (Fig. 3) is provided, mounted upon the upper members 32 of the carriage frame. Cylinder 80 contains piston 81 connected to piston rod 82 which operates upon a suitable cross head guide 83. Connected to piston 82 are ropes 84 and 85, rope 84 passing over fixed pulley 86 and being connected to the elevator frame at 87, rope 85 passing over fixed pulleys 88 and 189 and being connected to the elevator frame at 90.

For driving the machine along the tracks 23, an electric carriage motor 100 (Figs. 1 and 2) is provided. This motor drives a gear reducer 101 which drives a sprocket 102, which in turn drives a sprocket 103 mounted on one of the 40 wheel shafts through chain 204.

For supplying the cooling water and hydraulic water for operating the cylinders, above described, a second electric motor 104 is mounted on the frame of the carriage 20 driving centrifugal pump 105 (Fig. 3). Inlet 106 (Fig. 2) is provided from tank 33 to pump 105. Discharge 107 from pump 105 leads to the top of the machine from which flexible conduit 108 leads to the carrier 25 where it is connected to manifold 208 to which the flexible branch supply conduits 50 are connected. The discharge from the flexible branches 48 leads to a manifold similar to 208, which in turn is connected by a flexible conduit 109 to the spray 110 (Figs. 1 and 2) which returns the heated water to the tank 33 for cooling.

If desired, all the controls of the various operations are centered on one control board, indicated by 200 (Fig. 2). On this board may be provided suitable controls, indicated by 111 and 112, for motors 100 and 104. Also suitable valves 113 and 114 may be provided for operating cylinders 55 and 80. The control of carrier drive cylinder 55 is by valve 113 (Fig. 13). This valve may be an ordinary four-way valve having conduit 116 leading to the discharge of pump 105 and having conduit 117 leading either to the tank 33 or to the inlet of the pump. Conduit 214 leads to one end of the cylinder 55 and conduit 215 leads to the other end of the cylinder. Thus by operating the valve 113, water pressure may be applied to either end of the cylinder 55 and at the same time exhaust is applied to the other end.

Control of the elevator cylinder 80 is by valve 75

114 (Fig. 12). This valve may be an ordinary three-way valve, conduit 118 leading to the cylinder 80, conduit 119 leading to the discharge side of pump 105 and conduit 120 leading either to tank 33 or to the inlet of pump 105. Thus by the operation of valve 114, pressure may be applied to the cylinder 80 for raising the elevator device 24 or exhaust may be connected to the cylinder 80 for permitting the elevator device 84 to drop by its own weight.

- For operating the machine, the operator will move the entire machine along the front of the furnace to get the tools in line with a vertical tier of retorts. The elevator device will then be raised and the carrier operated to feed the tools into the retorts over the residue and slag indicated for example by 12 in Fig. 1. This tool may be moved to any intermediate point within the retort or to the inner end thereof, when the elevator will be lowered, causing the tool to yieldably, but forcibly engage the bottom of the retort. Movement of the carrier in the opposite direction will then move the tool outwardly, scraping the bottom of the retort and pulling the material along with it. As above stated, the tool 26 is a modified form of drag tool but, if desired, other tools may be substituted therefor. The water circulation through these tools prevents destruction thereof under the intense heat and scorifying atmosphere.
- An advantage of the present machine is that the tool may be fed into any point and the stroke of the tool may be of any length. The tool may pull out both slag and residue, and if material sticks at any point, the tool may be repeatedly moved over that point to free the material.

The flexible mounting of the tools on the carrier permits a forceful engagement between the tool and the retort and the tool continues to engage the retort even if the retort sags. It has been found that the drag tool alone is very effective when power is put behind it and ordinarily it would not be necessary to substitute other tools, such as, chisels and water lances.

If desired, an additional number of tools may be added for operating a greater number of retorts at the same time. For instance, a second tier of tools may be mounted alongside of the tier shown.

The construction of the machine is such that the parts will stand up under the high temperature and dusty atmospheres met in practice. The working parts of the operating cylinders are protected from dust and heat. The wire ropes used for operating the elevator device and carrier will stand up for long periods. If desired, cooling devices other than the spray and tank shown, such as, for instance, a radiator type of cooling device may be used.

While certain novel features of the invention have been disclosed and are pointed out in the annexed claims, it will be understood that various omissions, substitutions and changes may be made by those skilled in the art without departing from the spirit of the invention.

What is claimed is:

1. In apparatus for cleaning furnaces and the like, a tool, a carrier therefor, a support for said carrier, operating mechanism for moving said carrier toward and away from said furnace, said operating mechanism comprising a hydraulic cylinder having a piston and rod, a cross head connected to said rod, first and second sets of sheaves on said cross head, first and second sets of fixed sheaves, first and second ropes passing around the respective fixed and movable sheaves of each

set, each rope being connected at one end to said support and at the other end to said carrier for driving said carrier back and forth, said first rope having a safety mechanism comprising a movable pulley over which said first rope passes, a guide for said pulley, a counterweight for holding said pulley against the tension of said first rope, contacts engageable by excessive movement of said pulley, a hydraulic pump for supplying operating pressure to said cylinder, and a motor driving said pump controlled by said contacts.

2. In an apparatus for cleaning furnaces and the like, a tool, a carrier therefor, a support for said carrier, operating mechanism for said carrier comprising a set of sheaves, a rope on said sheaves and connected to said carrier and support, a cylinder and piston arrangement operating between said sheaves, a safety mechanism comprising a movable pulley over which the rope passes, a guide for said pulley, a counterpoise for holding said pulley against the tension of said rope and safety means operable by excessive movement of said pulley for controlling said operating mechanism.

3. In a cleaning mechanism, a bank of retorts arranged in substantially vertical tiers, a track-way extending along the front of said retorts, a carriage framework comprising a base member, means for supporting said base member for movement along said trackway, vertical side members supported by said base member, said side members being disposed on opposite sides of the track-way, guide members supported by said side members, an elevator comprising vertical slide members cooperating with said guide members, and also comprising a track member substantially parallel to said retorts, a carrier supported and riding on said track member, a plurality of drag tools arranged in a vertical tier for cleaning an entire vertical tier of retorts, there being one tool for each retort of the vertical tier, means for supporting said tools on said carrier, power devices located on said elevator for driving said carrier from one side member to the other to cause tools to enter and leave said retorts, power devices located on said carriage framework for imparting a limited vertical movement to said elevator and stop devices defining the upper and lower limiting positions of said elevator whereby the lower position of said drag tools causes them to rest on the bottom surface of their respective retorts, and the upper position of said drag tools is in line with the free space above the charge in the same retorts.

4. In a cleaning mechanism, a bank of retorts arranged in substantially vertical tiers, a track-way extending along said retorts, a carriage having wheels rollable along said trackway, guide members on said carriage, an elevator comprising vertical slide members cooperating with said guide members, and also comprising a track member substantially parallel to said retorts, a carrier riding on said track member, a plurality of vertically arranged drag tools for cleaning an entire vertical tier of retorts, there being one tool for each retort of the vertical tier, means for supporting said tools on said carrier, means for driving said carrier to cause said tools to enter and leave said retorts, independent means for imparting a limited vertical movement to said elevator, and stop devices defining the upper and lower limiting positions of said elevator whereby the lower position of said drag tools causes them to rest on the bottom surface of their respective retorts, and the upper position of said drag tools

is in line with the free space above the charge in the same retorts.

5. In a cleaning mechanism, a bank of retorts arranged in substantially vertical tiers, a track-way extending along the front of said retorts, a carriage framework comprising a base member, means for supporting said base member for movement along said trackway, inverted V-members supported by said base member, said V-members being disposed on opposite sides of the trackway, one of said V-members being disposed in proximity to the bank of retorts, guide members supported by said V-members, an elevator comprising vertical slide members cooperating with said guide members, and also comprising an inclined track member substantially parallel to said retorts, a carrier suspended from and riding on said track member, a plurality of drag tools arranged in a vertical tier for cleaning an entire vertical tier of retorts, there being one tool for each retort of the vertical tier, means for supporting said tools exclusively from the ends thereof on said carrier, power devices located on said elevator for driving said carrier from one V-member to the other to cause said drag tools to enter and leave said retorts, power devices located on the top of said carriage framework for imparting a limited vertical movement to said elevator, said power device having stops whereby the lower position of said drag tools causes them to rest on the bottom surface of their respective retorts, and the upper position of said drag tools is in line with the free space above the charge in the same retorts.
35. 6. In a cleaning mechanism, a substantially horizontal retort, a cleaning mechanism comprising a carrier, a tool substantially stationary with respect to said carrier, said tool comprising a long shaft having a transverse blade on its projecting end, means for mounting said shaft on said carrier at one end of the shaft only, whereby the

tool projects as a cantilever from said carrier, spring devices between said tool and said carrier to permit said tool to yield in case it engages an obstruction, means for imparting a limited vertical movement to said carrier, means to move said carrier toward and away from said retort to cause said tool to enter and leave said retort, and stop devices defining the upper and lower limiting positions of said carrier whereby the lower position of said tool causes it to rest on the bottom surface of its retort and the upper position of said tool is in line with the free space above the charge in said retort.

7. In a cleaning mechanism, a bank of retorts arranged in substantially vertical tiers, a cleaning mechanism comprising a carrier, a plurality of drag tools arranged in a vertical tier for cleaning an entirely vertical tier of retorts, there being one tool for each retort of the vertical tier, said tools being substantially stationary with respect to said carrier, said tools each comprising a long shaft having a transverse blade on its projecting end, means for mounting said shafts on said carrier at one end of the shafts only, whereby the tools project as cantilevers from said carrier, spring devices between said tools and said carrier to permit said tools to yield lengthwise and vertically in case they engage an obstruction, means for imparting a limited vertical movement to said carrier, means to move said carrier toward and away from said retorts to cause said tools to enter and leave said retorts, and stop devices defining the upper and lower limiting positions of said carrier whereby the lower position of said tools causes them to rest on the bottom surface of their respective retorts and the upper position of said tools is in line with the free space above the charge in the same retorts.

HUGH R. MACMICHAEL.
